US00D427635S

United States Patent [19]

Turchi et al.

[11] Patent Number: Des. 427,635

[45] Date of Patent: ** Jul. 4, 2000

[54] SURGICAL SIMULATION SYSTEM

[75] Inventors: **Mario Turchi**, Leonia, N.J.; **Diego Fontayne**, Montebello, N.Y.; **Richard Cunningham**, Arlington, Va.[73] Assignee: **HT Medical Systems, Inc.**, Rockville, Md.

[**] Term: 14 Years

[21] Appl. No.: 29/095,537

[22] Filed: Oct. 26, 1998

[51] LOC (7) Cl. 19-07

[52] U.S. Cl. D19/60; D19/62

[58] Field of Search D19/59, 60, 61, D19/62, 63, 64; 434/262, 267, 268, 272, 274

Primary Examiner—Martie K. Holtje

[57] CLAIM

The ornamental design for a surgical simulation system, substantially as shown and described.

DESCRIPTION

FIG. 1 is a top view in plan of one embodiment of a surgical simulation system showing our new design; FIG. 2 is a bottom view thereof in plan; FIG. 3 is a right side view thereof in elevation; FIG. 4 is a left side view thereof in elevation; FIG. 5 is a front view thereof in elevation; FIG. 6 is a rear view thereof in elevation; FIG. 7 is a perspective view thereof; FIG. 8 is an exploded view in perspective thereof; and, FIG. 9 is an exploded view in perspective of a second embodiment of a surgical simulation system showing our new design.
